(57) **CLAIM**

The ornamental design for an outlet enclosure, as shown and described.

DESCRIPTION

FIG. 1 is a top perspective view of the outlet enclosure, showing the new design;

FIG. 2 is a rear perspective view of the outlet enclosure thereof;

FIG. 3 is a front elevational view of the outlet enclosure thereof;

FIG. 4 is a rear elevational view of the outlet enclosure thereof;

FIG. 5 is a left side elevational view of the outlet enclosure thereof;

FIG. 6 is a right side elevational view of the outlet enclosure thereof;

FIG. 7 is a top plan view of the outlet enclosure thereof;

FIG. 8 is bottom plan view of the outlet enclosure thereof; and,

FIG. 9 is an exploded perspective view of the outlet enclosure thereof.

The broken lines shown represent unclaimed subject matter and form no part of the claimed design.
